HANGERS FOR TROUSERS

John D. Lee, Freeport, Pa.

Application May 5, 1954, Serial No. 427,751

1 Claim. (Cl. 223—95)

This invention relates to an improved hanger for men's trousers, and while primarily designed and intended for use by cleaner and dyer companies prior to and upon delivery of the cleaned garment to the customer, it will be obvious that the device is admirably adapted for use by hotels, motels, and the like, for the convenience of guests.

It is the common practice of clothes cleaners, after cleaning and pressing a pair of trousers, to drape the latter transversely of the knee area across the horizontal rod of a conventional type of coat hanger. Such suspension of the trousers invariably creates a discernible and undesirable crease across the draped flexure fold of the trousers, particularly if the trousers are stored away for prolonged periods of time while so suspended as is frequently done.

The invention contemplates among its important objects and advantages to provide a trousers hanger of the character described, which will neatly suspend the trousers at full length and thereby eliminate the liability of transversely creasing the trouser legs at the knee area, which may be readily and conveniently connected with the trousers and with a conventional type of coat hanger, which is so inexpensive in its construction that same may be discarded after having been used but once, and which affords considerable surface area for displaying advertising matter of the using organizations.

Further objects of the invention are to provide a trousers hanger device of the class stated, which is simple in its construction and arrangement, durable and efficient, compact, attractive in appearance, and comparatively economical in its manufacture and use.

With the foregoing and other objects in view which will appear as the description proceeds, the invention resides in the novel construction, combination and arrangement of parts herein described and illustrated in the accompanying drawing, but it is to be understood that the latter is merely illustrative of a preferred embodiment of the invention, and that changes in the form, proportions and details of construction may be resorted to that come within the scope of the claims hereunto appended.

In the drawing wherein like numerals of reference designate corresponding parts throughout the several views:

Figure 1 is a front elevational view, partly in section, of a trousers hanger, constructed in accordance with the invention, and illustrating the attachment of the device to a conventional type of coat hanger.

Figure 2 is an enlarged, normal end view of the trousers hanger.

Figure 3 is an enlarged fragmentary end view of the trousers hanger and showing the attachment of the latter with the trousers.

Figure 4 is a plan view of the blank used in the formation of the trousers hanger.

Figure 5 is a front elevational view of a slightly modified form of trousers hanger embodying the present invention.

The improved hanger for trousers is constructed of an integral sheet blank 1, and may be made of comparatively tough, stiff cardboard paper, plastic or composition ma-

terials, metal, or any other suitable sheet material to best meet conditions found in practice. The blank 1 is folded along three parallel extending lines, respectively indicated at 2, 3, and 4, to thereby form a pair of supporting panels, respectively indicated at 5 and 6, and a pair of attaching panels, respectively indicated at 7 and 8.

The blank 1 is rectangular in contour, and the panels 4, 5, 6, and 7 formed therefrom are all oblong rectangularly-shaped and are of uniform lengths and widths. The supporting panels 5 and 6 are folded downwardly against each other along the fold line 3, and are joined together along their top edges. The attaching panel 7 is folded upwardly against the adjacent outer face of the supporting panel 5, and is joined with the bottom edge of the latter along the fold line 2. In like manner, the attaching panel 8 is folded upwardly against the outer face of the adjacent supporting panel 6, along the fold line 4.

It will be readily apparent that, by folding the associated panels 5, 6, 7, and 8 together, in the manner above set forth, an oblong rectangularly-shaped hanger is formed, with the top edges of the attaching panels 7 and 8 being free, and provides a structure which is substantially W-shaped in transverse section, as clearly illustrated in Figure 2.

The trousers hanger is connected with a conventional type of coat hanger 9 by simply straddling the cross rod 10 of the latter with the supporting panels 5 and 6, whereby the cross rod 10 will seat against the under face of the joined tops of the supporting panels 5 and 6. The upper corners of the supporting panels 5 and 6 are bevelled, as indicated at 11, to form a recess the walls of which act to grip the cross rod 10 and thereby diminish the tendency of the trousers hanger to slip in the longitudinal direction on the cross rod 10 from its centrally mounted position on the latter.

Trousers are connected to the trousers hanger by simply inserting respective attaching panels 7 and 8 beneath the one-half inner portion of the cuffs 12 of respective trouser legs 13, as shown in Figure 3. This is readily accomplished as the top edges of the attaching panels 7 and 8 are free and therefore may be conveniently inserted into the trouser cuffs.

As the sides of the trouser cuffs are usually stitched to the trouser legs to maintain their position against the latter, each of the attaching panels 7 and 8 is formed with a deep, centrally disposed recess 14, which extends vertically and has an open upper end, and which provides the necessary clearance for receiving the stitched attachment of the cuff with the trouser leg when the attaching panels 7 and 8 are inserted into the trouser cuffs. The upper ends of the side walls of the recesses 14 are preferably rounded, as indicated at 15, to facilitate the entrance of the stitched attachment of the cuffs into the recesses 14.

A centrally disposed, longitudinally extending slot 16 is formed in the top juncture of the supporting panels 5 and 6 to allow the attachment of the trousers hanger in other ways to a coat hanger or to various other types of suspension elements than by straddling the cross rod 10 of a coat hanger in the manner stated. As shown in dot and dash lines in Figure 1, the trousers hanger may be attached to the coat hanger 9 by passing the upper portion of the latter through the slot 16. Further, as shown in Figure 5, the trousers hanger may be employed in connection with a special suspension element comprising a hook 17, which is attached to the center of a horizontally extending cross bar 18 having upturned ends 19 and engaging beneath and the ends of the top juncture of the supporting panels 5 and 6.

As shown in Figure 5, the fold of the attaching panels 7 and 8 with the bottom edges of respective supporting panels 5 and 6, may be reinforced by means of staples 20, which extend through respective supporting and at-

taching panels at positions close to the bottom juncture of the attaching panels with the supporting panels. Such reinforcing means will minimize the spread of the attaching panels from the supporting panels due to the weight pull of the trousers suspended from the attaching panels, and will permit the use of lighter sheet materials in the construction of the device.

It will here be noted that, the outer exposed surfaces of the attaching panels 7 and 8 provide considerable available area, which obviously may be utilized for displaying printed advertising matter or the like appertaining to the business of the person or organization in any way using or distributing the improved trousers hanger.

The present invention provides a most efficient device of its kind, which may be economically constructed and successfully employed for the purpose and in the manner herein set forth.

What I claim is:

An attachment for a garment hanger having a horizontally extending portion to receive the attachment, comprising a trousers suspension member constructed of an integral sheet of tough stiff material, said member folded along three parallel lines extending in the longitudinal

direction to form a pair of downwardly disposed supporting panels and a pair of upwardly disposed attaching panels, said panels being oblong rectangularly-shaped and uniform in length and width, said supporting panels positioned flatly against each other and joined together at the tops thereof along the center fold line, said attaching panels positioned flatly against the outer face of respective supporting panels and having the bottoms thereof joined with the bottoms of respective supporting panels, the joined top of the supporting panels being provided with a longitudinally extending slot for receiving and attaching the garment hanger with said member, each of said attaching panels provided with a centrally disposed transversely extending recess opening at the free top thereof, and reinforcing means engaged near the juncture of each of said attaching panels and the adjacent supporting panel for holding said panels flatly against each other.
